UNITED STATES PATENT OFFICE

2,473,753

MICROTOME AND ELECTROSTATIC DIS-
PERSAL APPARATUS THEREFOR

Howard R. Johnson, Baltimore, Md.

Application November 20, 1946, Serial No. 711,103

6 Claims. (Cl. 88—40)

1

This invention relates to improvements in electrostatic dispersal units.

An object of the invention is to provide an improved electrostatic dispersal unit for use in connection with microtomes for setting up an alternating magnetic field about a specimen holder and a cutter which will create an eddy current in the specimen holder and cutter so that the charges on the cutter will tend to neutralize the charges on the specimen and the specimen may be cut in a more precise manner than was heretofore possible.

Another object of the invention is to provide an improved electrostatic dispersal unit for microtomes and any other specimen cutting apparatus including means for setting up an alternating magnetic field between the specimen holder and cutter which will create an eddy current in the holder and cutter, and means including a rotatable roll formed of Bakelite or any other desired insulating material which will be slowly revolved by a suitable driving means connected to the microtome operating mechanism, whereby the thin specimens as they are sliced from the object will be fed in chain form over said roller to a suitable collecting receptacle.

A further object of the invention is to provide an improved mechanism for use with a microtome for neutralizing the static charges between a cutter and specimen, said mechanism including means for setting up an eddy current field about the specimen object holder and cutter, a paper envelope disposable over the entire cutter except that portion of the cutter that actually cuts the specimens, and an insulated driven roller for feeding or discharging the specimens in chain form after being cut, to be received and collected in perfect condition, without appreciable static charges, in a suitable collecting container or receptacle from which the specimen will be removed and made up into microscopic slides.

Another object of the invention is to provide an improved electrostatic dispersal unit for microtomes which will be highly efficient in operation, and relatively inexpensive to manufacture and produce.

Other objects will appear as the description proceeds.

In the accompanying drawings which form a part of this application,

Figure 1 is a side elevation of a microtome with the improved electrostatic dispersal unit incorporated therewith;

Figure 2 is a plan view of a microtome being partly broken away to show the improved electro-

2

static dispersal unit and step-down transformer with circuit connections incorporated therein;

Figure 3 is a perspective view of the specimen object holder with a coil surrounding the shank portion of the same for setting up an eddy current field about said holder;

Figure 4 is a perspective view of the specimen cutting knife blade showing the paper insulation envelope surrounding the same, and

10 Figure 5 is a vertical sectional view through the holder with specimen object supported thereon and the cutting knife in the process of slicing off a specimen for use in making microscope slides.

Like characters of reference are used throughout the following specification and the accompanying drawings to designate corresponding parts.

In carrying out the invention, there is provided a microtome of a well known construction generally indicated by the reference numeral 1.

20 The microtome 1 is provided with the usual operating pulley wheel or drive wheel 2 on which a handle 3 is secured, or the wheel 2 which is provided with a peripheral groove 4 may be driven by a belt and electric motor (not shown) in the event that a considerable amount of sectioning has to be done.

The microtome 1 includes means for reciprocating the object holder 5 and for intermittently feeding the same forwardly after each specimen is cut, this mechanism being old in the art and is described only in sufficient detail to enable one skilled in the use of microtomes to clearly understand the application of the improved electrostatic dispersal unit to the microtome.

25 The object or specimen holder comprises a disc-shaped head 6 being provided with a plurality of spaced concentrically arranged projecting ribs 7 substantially V-shaped in cross section. The shank 8 of the specimen holder is formed with opposed flat sides 9 at its inner end for supporting the holder in the reciprocating object holder clamp 10.

30 A coil 11 of electric wire is wound about the intermediate shank portion of the specimen holder and is connected in series with the secondary winding 12 of a step-down transformer generally designated by the reference numeral 13, which has a primary winding 14 adapted to be connected by means of the electric conductor 15 with any suitable source of electric current supply (not shown), whereby when the coil 11 is energized, an eddy current field will be set up around the specimen holder and the cutting area adjacent thereto.

35 A specimen block 16 of wax or other desired

material having the specimen tissue embedded therein will be forced against the roughened outer face of the head 6 and will be firmly supported thereon.

An adjustable knife blade or cutter 17 is supported in position adjacent the specimen holding head 6, whereby when the microtome 1 is operated, a specimen block 16 will be fed forwardly after each specimen has been cut, prior to the downward movement of the holder head 6 to cause 10 the specimen block to engage and move downwardly over the fixed cutting knife blade 17 to effect the cutting off of the specimens.

An elongated paper envelope 18 is provided for completely surrounding and encasing the knife 15 blade 17, the same being open at one edge adjacent the cutting edge of the knife blade 17, and the sides of the envelope are cut out as at 19 centrally of its length to permit the unrestricted operation of the cutting blade knife as it is engaged by the specimen block 16. The envelope 18 serves as an insulating medium for the blade 17 tending to prevent conductive contact between the cutter 17 and the cutter holding clamp 18' of the microtome 1.

A guide roller 20 of Bakelite or any other desired insulating material is mounted on the shaft 21 which extends between the bearings 22 and 23 on the base of the microtome 1, and extends in parallel relation to the cutting blade 17. A pulley 24 is secured to one end of the shaft 21, and is connected by the belt 25 with a second pulley 26 on the shaft 27 connected with and driven by the microtome driving or operating mechanism.

In operation, the step-down transformer 13 is connected with any suitable source of electric current supply (not shown), and the specimen block 16 is secured to the face of the holder head 6. The microtome 1 is then set into operation, and the specimens will be sliced from the specimen block 16, each specimen 28 as it is cut engaging the adjacent edge of the preceding specimen, thereby forming a chain which will be fed over the insulated guide roller 20 relatively free of any static electricity charge which would cause the specimens to bunch together, thereby producing imperfect sections which are difficult to remove for observation, and which, due to the static charges thereon, will prevent satisfactory observation of the specimens when under a microscope. The chain of specimens 28 will be fed to any suitable container or receptacle from which they may be removed as desired and made into microscopic slides.

It has been found that when means for dispersing electrostatic charges from the area around the specimen and its cutting area are not provided, imperfect specimens will be sectioned. However, when an electrostatic dispersal unit is used similar to that forming the subject matter of the instant invention, perfect specimens or specimens free from static charges will be sectioned and perfect microscopic slides will be made possible.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. In combination with a microtome including a cutter as a part thereof, means carried by the microtome for holding a specimen relative to the cutter to be cut by the latter, and means supported on the microtome setting up an alternating magnetic field about the holding means and cutter, and for creating an eddy current in the holding means and cutter.

5 2. The combination of claim 1 wherein said second mentioned means includes a coil carried by the holding means and connected to a source of electric current, said coil being so positioned to envelop the holding means and cutter in a pulsating magnetic field, said holding means and said cutter being relatively reciprocable.

3. In combination with a microtome including a cutter, means for holding a specimen relative to the cutter to be sliced by the latter, a coil carried by the holding means and connected to a source of electric current for setting up an alternating magnetic field about the holding means and cutter and setting up an eddy current in the holding means and cutter, said cutter including a cutting edge, and means for insulating the cutter, the cutting edge of said cutter being exposed from the insulating means.

20 4. In combination with a microtome including a cutter and a cutter clamp, means for holding a specimen relative to the cutter to be sliced by the latter, a coil carried by the holding means and connected to a source of electric current for setting up an alternating magnetic field about the holding means and cutter and setting up an eddy current in the holding means and cutter, said cutter including a cutting edge, and a flexible covering of insulating material carried by and substantially covering the surface of the cutter, the cutting edge of said cutter being exposed from the insulated covering, said covering insulating said cutter from its clamp and said holding means including a head portion having projecting ribs for receiving a specimen block.

25 5. In combination with a microtome including a cutter and a driving member, means for holding a specimen relative to the cutter to be engaged by the latter, means carried by the microtome setting up an alternating magnetic field about the holding means and the cutter and for setting up an eddy current in the holding means and cutter, and an insulated conveyor operatively connected to the driving member of said microtome and disposed adjacent the cutter for guiding specimens in chain form as the same are cut by the cutter.

30 6. In combination with a microtome including a cutter, a driving member, means for holding a specimen relative to the cutter to be engaged by the latter, a coil carried by the holding means and connected to a source of electric current, said coil being so positioned to envelop the holding means and cutter in a pulsating magnetic field, and for setting up an eddy current in the holding means and cutter, said cutter including a cutting edge, an insulating covering for the cutter, the

35 cutting edge of said cutter being exposed from the insulating covering, and an insulated guide roller carried by the microtome adjacent the cutter and operatively connected to the driving member of the microtome for guiding specimens in chain form as the same are cut by the cutter, said holding means and said cutter being relatively reciprocable.

HOWARD R. JOHNSON.
